EXTENSION ROLLER SCREEN

Joseph B. Plaum, Toronto, Ontario, Canada

Application April 10, 1946, Serial No. 660,975
In Canada April 1, 1946

2 Claims. (Cl. 160—29)

1

My invention relates to improvements in roller screens for windows in which the screening material is unwound from a tensioned roller as the sash is being raised, and conversely, is wound on the roller in the lowering of the sash. More particularly the invention concerns a roller screen of the adjustable type for different sized windows.

An object of the invention is to provide an improved roller screen which can be readily adjusted to suit windows of different sizes, and which can be easily installed by a householder without the use of special tools.

A further object is to provide a roller screen which will completely enclose the opening supplied by a raised sash, and which will assure that no crevices exist by which insects may gain entrance.

These and other objects are attained by the novel construction and arrangement of the appliance described in the ensuing specification and shown in the drawing which forms a part thereof.

The drawing is illustrative of the selected embodiment of the invention, and it will be understood that such changes and departures as to details of the structure may be resorted to as come within the invention defined in the claims.

In the drawing,

Fig. 1 is a perspective view partly in section of the improved roller screen.

Fig. 2 is a vertical section on line 2—2 of Fig. 3.

Fig. 3 is a fragmentary elevational view of the roller screen showing the left end portion thereof, the case being denoted in section.

Fig. 4 is an end view of the roller screen with the screening material partly withdrawn from the casing in the raised position of the window-sash.

Fig. 5 is a front elevational view of Fig. 4.

Fig. 6 is a vertical section through the casing showing one of the rollers partly in section.

Referring to the drawing by reference characters, it will be seen that the roller screen comprises a casing, generally denoted by the numeral 1, applied to the lower portion of a sliding sash 8 of an ordinary window. The casing is of the telescopic type by which it is adapted for elongation and contraction in order that it may be adjusted to windows of different sizes. It is composed of the interfitting members 9 and 10, which are preferably fashioned of metal.

The member 9 slides within the member 10, and each independently of the other supports a roller having a length of screening material applied to it for winding and unwinding operations thereon. Highly flexible reticulate plastic is desirably

2

used as the screening material, but comparable screening of a conventional character may be employed according to the dictates of the manufacturer.

5 The rollers, indicated by 11 and 12, extend substantially the full length of the respective members 9 and 10, and are arranged one above the other so that there is an overlapping of the screening material at the inner ends of the rollers. 10 By utilizing screening material in two sections, one on each roller, the telescopic action of the casing is not interfered with in making the adjustment of the screen to a window. The overlap of said sections varies according to the adjustment made. The complementary sections of the screening material are indicated at 13 and 14 for the rollers 11 and 12, respectively. Both sections of the screening material are downwardly directed through a slot 15 in the bottom portion 15 of the casing, which slot is common to the members 9 and 10. The slot is discernible in Fig. 2.

The lower ends of the sections are each anchored to an upturned flange 16 of an attachment plate by means of a binding strip 17 and fastening elements 18. These plates, numbered 19 and 20, interfit and have telescopic parts made up of the tubular elements 21. The plates therefore can be relatively adjusted in conformity with any elongation and contraction of the casing as may be required to fit a window. The plates are detachably secured to the stool of the window by fastening elements 22, shown as thumb screws.

The rollers are each supplied with springs, as at 23, having the usual key pieces 24 by which they are tensioned in the unwinding operation. The key pieces are mounted in the outer end walls 25 of the members 9 and 10. The inner end of upper roller 11 is journaled on an ear 26 integral with or secured to the back wall, of the member 9. The inner end of the lower roller 12 is journaled on an ear 27 upstanding from the bottom portion of the member 10 and freely projecting through a slot 28 in the bottom portion of the member 9. This slot accommodates telescopic action of the members 9 and 10.

45 From the preceding description it will be understood that the overlapping arrangements of the rollers and the sections of the screening material constitutes an important feature of the invention. Another feature of importance is that means are provided to close off any opening that may exist at the sides of the screening material in the raised position of the lower sash. Although the casing will be mounted on the lower sash with its ends in close proximity to the

enclosing frame or jamb 29 of the window, the adjacent side edges of the screening material cannot extend to the adjoining faces 30 of the enclosing frame or jamb, and consequently there must be a space that should be closed off. The means for closing this space at each end of the casing comprises a tape or ribbon 31 of inelastic or elastic material wound upon a roller 32 with an end secured to the respect attachment plate by the elements 16 and 17 in a similar manner to that in which the screening material is anchored. Each roller is located in juxtaposition to the adjacent face 30 of the window frame 29 so that the tape thereon is in contact with the face 30 and in overlapping relation with the side edge portion of the screening material, as will best be seen from an inspection of Fig. 5.

Each roller is rotatably mounted on a pin 33 carried by an arm 34 pivoted to the casing by an element 35 at the underside thereof. Said arm is urged by a spring 36 to press the roller inwardly so that the tape or ribbon will be held in contact with the screening material. A tongue 37 rigidly depends from the casing to the rear of the screening material to support the same against the pressure of the roller.

The casing is preferably detachably applied to the window sash by means of devices located near the ends thereof. These attachment devices each comprise an ear 38 rigid with the back wall of the casing and projecting upwardly therefrom. The ear is inserted in a substantially U-shaped strap 39 horizontally arranged and secured by fastening elements, such as wood screws, to the respective vertical rail of the sash 8. The ear is of a length to project from the upper side of the strap and its top end is fitted with a spring-pressed pin 40 which in its projected position is engaged with the top edge of the strap to secure the ear with a latching action. To release the ear it is only necessary to depress the pin. The ear can then be withdrawn to effect removal of the casing from the sash.

Means are desirably supplied on the casing to secure the sash 8 in raised position. Such means are comprised of a catch device at each end of the casing in the form of a bar 41 slidably fitted in a bracket 42 secured to the bottom portion of the respective telescopic element of the casing. The bar is horizontally arranged and provided with a head 43 of rubber at its outer end for frictionally engaging the adjacent face 30 of the enclosing frame 29. A spring 44 operates to normally retain the bar in retracted position, and a lever cam 45 is pivotally supported at 46 with 55

its eccentric or cam face engaged with the inner end of the bar. By swinging the cam lever downwardly about its fulcrum the bar is outwardly urged to lock the sash against movement.

5 The invention provides a highly efficient and serviceable roller screen which can be manufactured at low cost.

What I claim is:

1. In a roller screen mounted in a window frame and having a casing extending horizontally between opposite side faces of a window sash in said frame and housing a spring roller from which is stretched screening material, said material having its free end attached to a horizontal element of said window frame; means for closing off the space between a side edge of the stretch of screening material and the adjacent side face of said window frame, said means comprising an arm pivoted at an end thereof on said casing and swingable to and away from said screening material, a roller mounted on the swinging end of said arm, a ribbon of pliant material wound on said roller and extended therefrom to overlap said side edge of the screening material, a free end of said ribbon being attached to said horizontal element, and a spring urging said arm and pressing said roller inwardly toward said screening material and holding the ribbon material on the roller in contact with the screening material to effect a friction drive for unwinding and winding of the ribbon according to the movement of the casing attendant upon the opening and closing of the window.

2. A roller screen as set forth in claim 1 in which a tongue rigidly depends from the casing to support the screening material against the thrust of the roller on which the ribbon of pliant material is wound.

JOSEPH B. PLAUM.
